(57) **CLAIM**

The ornamental design for a laryngeal mask, as shown and described.

DESCRIPTION

FIG. 1 is a first perspective view of a laryngeal mask showing my new design.

FIG. 2 is a top plan view thereof.

FIG. 3 is an enlarged back plan view thereof.

FIG. 4 is a first side view thereof.

FIG. 5 is a second side view thereof.

FIG. 6 is an enlarged front plan view thereof.

FIG. 7 is a bottom plan view thereof; and,

FIG. 8 is a second perspective view of the laryngeal mask of FIGS. 1-7 showing a movable member thereof in a different position.

The evenly broken lines in the drawings illustrate portions of the laryngeal mask that form no part of the claimed design. The dot-dot-dash broken lines in FIGS. 1 and 2 indicate boundary lines which enclose areas that form no part of the claimed design.
